Term of patent 14 years

(Cl. D33—14)

FIG. 1

FIG. 2

FIG. 3

FIG. 4

FIGURE 1 is a perspective view of a table illustrating my design;

FIGURE 2 is a side elevational view thereof;

FIGURE 3 is an end view; and

FIGURE 4 is a perspective view of the table with the under shelf removed.

The characteristic features of the design reside in the combination on the table disclosed of the four upwardly turned bounding edges of the table top which are arcuate in their respective lengthwise directions and gradually merge at their corner extremities, together with a removable under shelf formed of open work, all as shown.

I claim:

The ornamental design for a table, as shown and described.
